UNITED STATES PATENT OFFICE.

DREW REYNOLDS, OF MARION, ILLINOIS.

TELESCOPIC HANDLE FOR COMBINED SCRAPERS AND TAMPERS.

1,365,851.

Specification of Letters Patent. Patented Jan. 18, 1921.

Application filed January 31, 1920. Serial No. 355,454.

To all whom it may concern:

Be it known that I, DREW REYNOLDS, a citizen of the United States, residing at Marion, in the county of Williamson and State of Illinois, have invented certain new and useful Improvements in Telescopic Handles for Combined Scrapers and Tampers, of which the following is a specification, reference being had to the accompanying drawings.

This invention relates to the art of mining tools, and particularly to an improved extensible telescoping handle for miners' scrapers and tampers, and an object of the invention is to provide a handle of this character which is made extensible so that a miner's tool may be held at any desired length from the hand of the user.

Another object of the invention is to provide an extensible handle, which is capable of attachment to various mining tools, especially tampers and scrapers, so that when the miner moves from one place to another it may be accomplished with greater ease and less inconvenience, as it is possible to collapse the handle to a very small compass hardly much longer than the tool, such as the tamper or the scraper, and may be easily carried in a tool box, which can be carried very easily.

A further object of the invention resides in the fact that an extensible handle for use in connection with a plurality of tools, is by far superior to carrying a plurality of tools, each having separate rigid handles.

A still further object of the invention is that a single extensible handle with a plurality of mining tools can be put on the market for a relatively low cost with a remuneration of a reasonable profit, and at a considerably less outlay than by manufacturing a plurality of tools having their own handles.

The invention still further aims to provide a very simple, efficient and practical extensible and telescoping handle comprising a plurality of handle sections, and including a novel form of holding connection or means between the handle sections, so that the handle will be rigid when in use, and so that the sections may be easily collapsed, when the handle is in storage or carried in a miner's tool chest.

An additional object of the invention is to provide a holding connection between the

sections of such construction that the sections can be very easily manipulated for collapsing them, when it is desired to place the handle in the tool box. This folding connection is so constructed and includes means, whereby it is unnecessary to hold the latch of the connection the entire time the handle sections are being telescopically collapsed. It is only necessary to raise the latches one at a time, and impart a slight turn to each section, then they may be easily and quickly collapsed by applying pressure upon both ends of the handle. The extensible handle may be adjusted to different lengths as may be found necessary, by those using the handle.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view in elevation of the improved extensible handle showing the handle sections extended,

Fig. 2 is a view in elevation of the extensible handle showing the sections collapsed,

Fig. 3 is a sectional view on line 3—3 of Fig. 1,

Fig. 4 is a detail perspective view showing the joint between two of the sections of the handle, and

Fig. 5 is a sectional view on line 5—5 of Fig. 4.

Referring more especially to the drawing, 1 designates a tool shank which may terminate in any suitable mining tool, such as a scraper or tamper, as indicated at 2. The shank 1 merges into the handle, which comprises a plurality of handle sections 3, 4, 5 and 6. In fact, the tool shank 1 merges in any suitable manner into the smaller tubular handle section 3. The handle section 6 at one end merges into a tamper 7, which may be constructed of any suitable metal, and is provided with a copper tip 8. Obviously, it will be noted the handle carries

two different kinds of tools, for instance, a scraper on one end, and a tamper on the other. If desired, other sections similar to 3 and 6 may be provided and may have 5 other forms of tools, other than scrapers and tampers.

The handle sections are provided with a plurality of transversely disposed segmental or arcuate slots 9 at spaced intervals 10 throughout the sections. These slots or notches at certain ends of their bottoms have shoulders 10, and from the shoulders the bottoms of the notches or slots incline, so that a catch may slide upon the incline 15 and then fall into engagement behind the shoulder.

The sections of the extensible handle are provided with longitudinally extending grooves 11, which are disposed adjacent certain 20 of the ends of the transversely disposed slots or notches so that the inclined bottoms of the notches or slots will merge into the longitudinal grooves.

Certain of the ends of the handle sections, 25 excepting the handle section 3, are provided with spring tongues 12, which form integral parts with the handle sections. These integral spring tongues 12 are formed by slitting the tubular sections as indicated at 13, 30 and the ends of the spring tongues terminate in lateral lugs 14, which engage the transversely disposed arcuate or segment slots, that is to say, when the handle sections are extended. In fact, the lateral lugs 35 14, when the handle sections are adjusted to the length desired, engage behind the shoulders of said arcuate or segment slots or notches so as to hold the sections in their extended positions. However, when it is desired to collapse the sections, and to adjust 40 the sections into a different length, then each of the spring tongues may be pulled from the transverse slots or notches, sufficiently to pass over the shoulders, when a partial turn 45 is imparted to the sections. The tubular handle sections may be further rotated, until the lugs 14 are in a position to enter the longitudinal grooves or slots, and then the handle sections may be collapsed to other extended 50 positions, or to a collapsed position, for storing the handle away or for placing the handle in the miner's tool box.

The invention having been set forth, what is claimed as new and useful is:

55 1. In an extensible handle for tools, the combination with a plurality of tubular handle sections telescopically united, of tools carried by the remote ends of the end handle

sections, said handle sections having transversely disposed arcuate slots or notches 60 provided with a retaining shoulder, the corresponding ends of certain of the handle sections having spring tongues provided with lateral lugs engaging into said slots or notches in engagement with and behind the 65 shoulders, to hold the handle sections extended and against rotation relatively to each other, the handle sections having longitudinally extending grooves, positioned adjacent certain of the ends of the arcuate slots 70 or notches, which are provided with inclined bottoms merging into the longitudinal grooves so that by lifting the tongue over the shoulders, the lateral lugs may cam into engagement with the longitudinal grooves, 75 for the purpose of collapsing the handle sections.

2. In an extensible handle for tools, the combination with a plurality of tubular handle sections, the end sections having their 80 farther ends terminating in mining tools, slot and spring device connections between the handle sections to hold them in extended positions, said handle sections having longitudinal grooves extending adjacent certain 85 of the ends of the slots of said connections, said slots of said connections having inclined bottoms merging into the longitudinal grooves, to facilitate the collapsing of the tubular handle sections, without holding the 90 spring devices of said connections by hand, while the sections are being collapsed.

3. In an extensible handle for tools, a plurality of tubular handle sections telescopically united, certain of the sections having on their exterior surfaces longitudinally extending grooves provided with lateral 95 grooves arcuate in form, each of said lateral arcuate grooves having a closed end remote from where the grooves merge into the longitudinal grooves, said closed end having a shoulder, corresponding ends of the sections being provided with parallel slits causing spring tongues to be formed between the slits, said tongues having lateral lugs adapted to engage the longitudinal grooves when collapsing or extending the handle section, and when the sections are either in collapsed or extended positions, said lugs adapted to engage the lateral arcuate grooves by imparting a partial rotary movement to each section until the lugs engage said shoulders. 100 110

In testimony whereof I hereunto affix my signature.

DREW REYNOLDS.
